FLIER CONSTRUCTION

Michael J. McHale, Scranton, Pa.

Application September 5, 1940, Serial No. 355,483

5 Claims. (Cl. 57—116)

My invention relates to fliers of the type used with spinning machines and more particularly to an improved flier block arrangement having means for attaching and supporting the flier wires.

One of the objects of the present invention is to provide a flier block structure constructed and arranged to permit use of a single flier wire having arms extending outwardly on the same side of the block. In the use of flier wires of this character, it is necessary to provide means for balancing the block, that is to say, means to compensate the unbalanced forces due to the projection of the flier arms on the same side of the block.

Heretofore it has been suggested to use balancing devices and in application Serial No. 283,880, filed September 30, 1939, I have disclosed a balance in the form of a loop adapted for use with a flier block having a metal flier wire supporting plate. Considerable demand has recently developed for a lightweight flier block adapted for use with a single wire arranged so that the horizontal and drop arms extend outwardly on the same side of the block. While in some circumstances the winding operation requires a flier arrangement of this type it is desirable from the standpoint of efficiency and economy to have a block adapted for general application, that is, a block which can also be used with a single wire having arms on opposite sides of the block or with conventional double flier wires.

After considerable research and experimentation, I have found that the forces developed by the arms on the same side can be balanced or otherwise compensated by attaching a member to the block in a plane above the plane of the arms of the flier wire and extending outwardly therefrom in a direction opposite the arms. The present invention also comprehends the provision of a block structure adapted for use with conventional arrangements of single and double wires.

An object of my invention is to provide an improved flier block.

Another object of my invention is to provide a flier block adapted for use with a single flier wire having arms extending outwardly on the same side of the block.

Still another object of my invention is to provide a flier block adapted for use with a single flier wire, a double flier wire or a single wire with arms on the same side of the block.

Yet another object of my invention is to pro-

vide an improved flier block having flier wire balancing means associated therewith.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawing:

Figure 1 is an elevational view, partly in section, showing my improved flier in operative position on a bobbin spindle.

Fig. 2 is a plan view of the flier block shown in Fig. 1; and

Fig. 3 is a perspective view of the flier block showing a flier wire and balancing member mounted thereon.

Referring to the drawing and more particularly to Fig. 1, there is shown a flier arrangement associated with a bobbin 1, mounted in operative position on a suitable spindle 2, of a conventional winding machine. The bobbin is provided with a head member 3, and a centrally recessed portion 4, adapted to receive a ferrule 5, having an aperture 6, through which the flier foot is inserted. The flier block designated generally by numeral 7, comprises a centrally apertured body portion 8, having a base portion 9, and head portion 10. Between the base and head portions, in the vicinity of the base, there is provided a peripheral flier wire receiving groove 11, adapted to form a seat for a flier wire. Between the base of the head portions of the block, above the flier wire receiving groove, there is also provided a peripheral groove 12, adapted to receive a balancing member, arranged to compensate the unbalanced forces due to the projection of the flier wire arms on the same side of the block.

Referring to Figs. 2 and 3, it will be noted that the flier wire is formed with a central block engaging section 13, which seats in the peripheral groove 11, and that the arms 14 and 15, of the wires are entwined as at 16, in the vicinity of the block. The wire is thus securely attached

to the block by twisting the arms so that a fairly tight fit is obtained. In order to prevent relative movement of the flier wire with respect to the block, that is to say, to prevent a rotative movement of the wire on the block, a suitable pin 17, is provided. As shown in Fig. 1, flanges 18, 19 and 20, which define the peripheral grooves 11 and 12, are bored to form concentric openings in the flange for the reception of pin 17, which in the seated position extends into groove 11, between the arms of the wire, acting as a stop to prevent rotation of the flier wire with respect to the block.

In the use of a single wire, having its arms extending outwardly on the same side of the block, it has been found that the unbalanced forces developed by this arrangement of the wire must be compensated, otherwise uniform tension on the thread during the winding operation cannot be obtained. In order to balance out the undesirable forces, the flier block of the present invention is provided with a balancing member in the form of a wire loop adapted to seat in the upper peripheral groove 12, in the vicinity of the head portion of the block.

As will be seen in Figs. 2 and 3, the balancing member designated generally by numeral 21, comprises a loop formed from wire, having arms 22, provided with curved portions 23, constructed and arranged to seat in the upper peripheral groove 12. The curved portions 23, terminate in ends 24, adapted to seat in openings 25, formed at diametrically opposite points in the body of the block and in the upper peripheral groove portion.

It will be understood that the flier wire balancing member will be formed from wire of suitable gauge to effect the required balancing of undesirable forces developed by the flier wire arms. The arms 22, are spaced apart sufficiently to provide tension on the curved portions 23, when these portions are in seated position in groove 12, so that ends 24, will be maintained within the recesses 25. By means of this arrangement, the balancing member is securely held in fixed position on the block and undesirable flexing of the member is prevented.

Referring to Fig. 3, it will be noted that the base portion of the flier block is formed with an eccentric foot 26, which is adapted for insertion into the aperture 6, formed in the ferrule 5 (Fig. 1), whereby the block is maintained in operative position with respect to the bobbin, during the winding operation.

In assembling the flier, the flier wire is applied to peripheral groove 11, with its central block engaging section 13, in seated position therein, the arms 14 and 15, of the wire being there-afterwards twisted to provide a tight seat between the looped portion of the wire and its contact portion with the body of the block and pin 17, thus locking the wire and preventing its rotation with respect to the block. The wire balancing member 21, is then applied to the block by spreading arms 22, a sufficient distance to permit insertion of ends 24 in openings 25, and upon release, the curved portions 23, seat in the upper peripheral groove 12.

It will be appreciated that the flier block of the present invention is of general application, that is to say, it may be used with single or double wires of the conventional type, or in certain circumstances requiring the use of a wire having arms on the same side of the block, the balancing arrangement may be used.

While I have shown and described the pre-

ferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A flier for spinning machines and the like, comprising a centrally apertured body member having base and head portions thereon, a peripheral flier wire receiving groove formed in the body member between the base and the head portions, a flier wire seated in said groove, a second peripheral groove formed in the body above said flier wire receiving groove, said second groove having openings formed therein at diametrically opposite points, and a flier wire balance seated in said second groove, comprising a loop having arms formed with inwardly turned end portions, said ends being seated in the openings formed in the groove.

10 2. A flier for spinning machines and the like, comprising a centrally apertured body member having base and head portions thereon, a peripheral flier wire receiving groove formed in the body member between the base and the head portions, a flier wire seated in said groove having its arms extending outwardly on the same side of the body of the flier block, a second peripheral groove formed in the body above said flier wire receiving groove, said second groove having openings formed therein at diametrically opposite

20 points, and a flier wire balance comprising a loop member having arms formed with inwardly turned end portions, said ends being seated in the openings formed in the groove, the arms of the loop extending outwardly from the block in a direction opposite the flier wire arms.

25 3. A flier for spinning machines and the like, comprising a centrally apertured body member having base and head portions thereon, an eccentric foot member formed on said body adapted for insertion into a head of a bobbin, a peripheral flier wire receiving groove formed in the body member between the base and the head portions, a flier wire seated in said groove having its arms extending outwardly on the same side of the block, a second peripheral groove formed in the body of the block above the first groove, said second groove having openings formed therein at diametrically opposite points, and a flier wire balance comprising a loop member having arms formed with inwardly turned end portions, said ends being seated in the body of the block in a direction opposite the flier wire arms.

30 4. A flier for spinning machines and the like, comprising a centrally apertured body member having base and head portions thereon, a peripheral flier wire receiving groove formed in the body of the block between the base and head portions, a flier wire seated in said groove, having a central block engaging section and arms extending outwardly therefrom, the arms of the wire being entwined in the vicinity of the block, the free ends of the arms extending outwardly on the same side of the block, a second peripheral groove formed in the body of the block above said flier wire receiving groove, said second groove having openings formed therein at diametrically opposite points, and a flier wire balance comprising a loop member having arms formed with inwardly turned end portions, said ends being seated in the openings in the groove,

the arms of the loop extending outwardly from the block in a direction opposite the fier wire arms.

5. A fier for spinning machines and the like, comprising a centrally apertured body member having base and head portions thereon, an eccentric foot member formed on said body adapted for insertion into the head of a bobbin, a peripheral fier wire receiving groove formed in the body of the block between the eccentric foot and head portion, a fier wire seated in said groove, having a central block engaging section and arms extending outwardly therefrom, the arms of the fier wire being entwined in the vicinity of

the block, the free ends of the arms extending outwardly on the same side of the block, a second peripheral groove formed in the body of the block above said fier wire receiving groove, said second groove having openings formed therein at diametrically opposite points, and a fier wire balance comprising a loop member having arms formed with inwardly turned end portions, said ends being seated in the openings formed in the groove, the arms of the loop extending outwardly from the block in a direction opposite the fier wire arms.

MICHAEL J. McHALE.
